ROTARY SHEARING HEAD

Harry L. Collins, St. Louis, Mo., assignor to
 Knapp-Monarch Company, St. Louis, Mo., a
 corporation of Missouri

Application May 18, 1938, Serial No. 208,644

1 Claim. (Cl. 30—43)

An object of my invention is to provide a very simple rotary shearing head involving a minimum number of working parts and utilizing centrifugal force to maintain shearing contact between inner cutter blades and an outer cutter cylinder of the shearing head.

Another object is to provide a shearing head comprising an outer cylinder perforated to receive hair to be cut and an inner cutter member comprising a rotating body member and shearing blades which are so movable relative thereto by centrifugal force whereby they are maintained in shearing engagement with the inner surface of the outer cylinder during operation.

A further object is to provide in combination with a motor and a motor shaft, shearing means comprising an outer cylinder mounted on the motor over the motor shaft and an inner cutter having a body member provided with substantially radially extending slots in which cutter blades are slidably mounted for shearing coaction with the inner surface of the outer cylinder.

With these and other objects in view my invention consists in the construction, arrangement and combination of the various parts of my shearing head, whereby the objects contemplated are attained, as hereinafter more fully set forth, pointed out in my claim, and illustrated in the accompanying drawing, in which:

Figure 1 is a side elevation of a rotary shearing head embodying my invention and showing it mounted on a motor.

Figure 2 is an enlarged sectional view on the line 2—2 of Figure 1.

Figure 3 is a sectional view on the line 3—3 of Figure 2.

Figure 4 is a perspective view of the body member and cutter blades of my shearing head.

Figure 5 is a side elevation of a modified form of structure; and

Figure 6 is a sectional view on the line 6—6 of Figure 5.

On the accompanying drawing I have used the reference character M to indicate a motor such as the small type adapted to be used as a handle for dry shavers as now in general use. The motor M is supplied with electric current from a plug 10 and supply cord 12 in a well-known manner, which requires no specific description as it forms no part of my present invention.

The motor housing M has a neck 13 on its upper end on which I mount my rotary shearing head. The motor has a shaft 14 journaled in the neck 13 and extending from the upper end of the neck as shown in Figure 3. My rotary shear-

ing head comprises an outer cylinder C, a body member B and shearing plates 15. The outer cylinder C has a flared portion 16 adapted to fit the neck 13 and is normally retained in position relative thereto by a spring-pressed ball 17. The spring is indicated at 18 and the ball is adapted to enter a socket 19 formed in the cylinder as shown in Figure 3.

The body member B has a bore 20 receiving the motor shaft 14. The body member may be secured to the motor shaft in any suitable manner such as by a pin 21. The body member B has slots 22 which slidably receive the blades 15. Two of the slots are illustrated although one, three or more can be used if desired. The cylinder C has a plurality of perforations 23 therein which may be round as illustrated in the drawing or slotted or any other shape desired. These are for the purpose of receiving the hair to be cut by the shearing head.

The wall of the cylinder C as shown in Figure 2, is preferably of varying thickness which may be accomplished by forming its interior surface off center relative to its outer surface. This results in different portions of the cylinder permitting reception of the hair to different depths. For instance at the point b in Figure 2 a very close shave can be secured as the thickness of this portion of the cylinder wall is minimum. At c, d, and e, progressively greater thicknesses of the wall permit less extension of the hair through the cylinder C and consequently a less close shave.

The hair which is clipped off is expelled through an opening 24 in the upper end of the cylinder C so as to prevent the hair from clogging the interior of the shearing head to such an extent that it will not operate.

During operation the blades 15, since they are free to slide in the slots 22, will be urged outwardly by centrifugal force into shearing engagement with the inner surface of the cylinder C. Such centrifugal force results from rapid rotation of the motor shaft 14 which preferably rotates at a relatively high speed (about 7000 R. P. M.). The centrifugal action therefore eliminates the necessity of any spring means or other mechanism to maintain shearing contact during operation of the shearing head.

As shown in Figure 5 the cylinder C has a bulge 25 or rib 25 which serves to strengthen the cylinder against bending particularly where it is made of relatively thin metal and also serves as an indicating means for the operator as to which side is the back side of the shearing head. This facilitates using the proper portion of the pe-

riphery of the cylinder to secure the desired type of shave during operation of the shearing head.

As above pointed out, centrifugal force produced by rotation of the shearing motor results in the elimination of auxiliary means to bias the blades to engage the outer cylinder. The speed of rotation can be varied to vary the degree of shearing contact pressure between the blades and the cylinder and the operator is always insured that good contact will be maintained without danger of spring breakage or other trouble.

Some changes may be made in the construction and arrangement of the parts of my device without departing from the real spirit and purpose of my invention. Accordingly I intend to cover by my claim, any modified forms of structure or use of mechanical equivalents which may be reasonably included within their scope.

I claim as my invention:

In a shearing device, the combination of a support, a housing supported thereby and ro-

tating cutter means therein, said housing having an internal surface formed as a right circular cylinder and having an outer surface formed substantially as a right circular cylinder, said cylinders being formed on offset parallel axes, the resulting relatively thin portion of said housing being apertured to form a skin-contact shear plate, said rotating cutter means comprising a body element having radially extending slots therein, and cutter blades freely slidable in said slots, each of said cutter blades consisting of a generally rectangular block having a straight line cutting edge, and having said cutting edge extending longitudinally of said housing and engaging with the inner surface thereof when said cutter means is rapidly rotated; an opening in the outer end of said housing, and means in said support for rapidly rotating said cutter means on the axis of the inner surface of said housing.

HARRY L. COLLINS.
